(57) **CLAIM**

The ornamental design for the physical therapy balance board, as shown and described.

DESCRIPTION

FIG. 1 is an elevated isometric view of a physical therapy balance board showing the new design;

FIG. 2 is a left side isometric view of the physical therapy balance board as shown in FIG. 1;

FIG. 3 is a right side isometric view of the physical therapy balance board as shown in FIG. 1;

FIG. 4 is a front isometric view of the physical therapy balance board as shown in FIG. 1;

FIG. 5 is a rear isometric view of the physical therapy balance board as shown in FIG. 1;

FIG. 6 is a top view of the physical therapy balance board as shown in FIG. 1;

FIG. 7 is a bottom view of the physical therapy balance board as shown in FIG. 1;

FIG. 8 is a left rear side view of the physical therapy balance board taken 45 degrees counterclockwise from the left side view of FIG. 2;

FIG. 9 is a right front side view of the physical therapy balance board taken 45 degrees counter clockwise from the right side view of FIG. 3;

FIG. 10 is a left front side view of the physical therapy balance board taken 45 degrees clockwise from the left side view of FIG. 2; and,

FIG. 11 is a right rear side view of the physical therapy balance board taken 45 degrees clockwise from the right side view of FIG. 3.
